UNITED STATES PATENT OFFICE.

JOSHUA RUFUS WALES, OF MARLBOROUGH, MASSACHUSETTS.

BOOKBINDING.

SPECIFICATION forming part of Letters Patent No. 605,364, dated June 7, 1898.

Application filed October 2, 1897. Serial No. 653,882. (No model.)

To all whom it may concern:

Be it known that I, JOSHUA RUFUS WALES, a citizen of the United States, residing at Marlborough, in the county of Middlesex and State 5 of Massachusetts, have invented certain new and useful Improvements in Bookbinding; and I do hereby declare the following to be a full, clear, and exact description of the invention, such as will enable others skilled in the 10 art to which it appertains to make and use the same.

My invention is an improvement in means for connecting the covers with the back proper of a book, and the same is hereinafter set forth. 15 In the drawings, Figure 1 is a perspective view of a book having my improvement partly applied, one cover being removed. Fig. 2 is a cross-section on line 2 2 of Fig. 1. Fig. 3 is an enlarged cross-section of a book, showing 20 my improvement as completely applied to both covers. Fig. 4 is a plan view of a portion of the back-binding.

The back-binding A consists of an oblong strip or piece of thin leather or suitable fabric, whose side edges are slitted transversely 25 to form the divided tongues 4 and 5. When the binding A is applied to the body of a book consisting of bound leaves 3, it is pasted lengthwise on the back thereof, as shown in Fig. 1, and the tongues 4 are lapped and pasted upon the outer side of the covers 1 and 2, as shown in Fig. 3, while the adjacent alternate tongues 5 are similarly lapped and pasted upon the fly-leaves of the book beneath the 35 covers 1 and 2, as shown in all the figures.

I show the tongues 4 as standing vertical in Fig. 1 for the sake of enabling the invention to be more clearly understood.

To render the binding still firmer and perfectly secure without materially affecting the 40 flexibility of the hinge connection of the covers 1 and 2, I apply bands or tapes 7, as shown—that is to say, the same are applied between the back of leaves 3 and the piece 6 and passed through slits 8 in the back-binding, or, more strictly speaking, through slits 45 in the portions 4 of the binding, which are lapped on the outside of the covers 1 and 2. The ends of such tapes 7 are shown free in Figs. 1 and 2 and as glued down on the parts 50 4 in Fig. 4, and thus the binding is complete. This combination and arrangement of the tapes with the binding parts 4 and 5 and the covers 1 2 secures the latter in the firmest possible manner and forms a hinge of the 55 most flexible yet durable kind.

What I claim is—

The combination, with the body of a book and the covers proper, of the back-binding, composed of the strip of fabric having transversely-separated portions or tongues, 4 and 5, which are secured on the covers and body, respectively, and the tapes 7, which are arranged within such binding, and passed through longitudinal slits in the tongues 4, 60 65 and glued down on such tongues, as shown and described.

In testimony whereof I have signed this specification in the presence of two subscribing witnesses.

JOSHUA RUFUS WALES.
